Primary Examiner — Catherine S Posthauer(74) Attorney, Agent, or Firm — Leydig, Voit & Mayer, Ltd.(57) CLAIM

The ornamental design for a label for food packaging, as shown and described.

DESCRIPTION

The patent or application file contains at least one drawing executed in color. Copies of this patent or patent application publication with color drawing(s) will be provided by the Office upon request and payment of the necessary fee.

The FIGURE is a front view of a label for food packaging showing our new design.

The rear surface of this design is unornamented and therefore not illustrated.

The logo including the black pot with handles, a spoon, and a set of chopsticks, forming part of the claimed design, is a registered trademark of CJ CHEILJEDANG CORPORATION.
